UNITED STATES PATENT OFFICE.

ALBERT B. DICK, OF LAKE FOREST, ILLINOIS, ASSIGNOR TO A. B. DICK COMPANY,
OF CHICAGO, ILLINOIS, A CORPORATION OF ILLINOIS.

STENCIL-PRINTING MACHINE.

No. 873,847.

Specification of Letters Patent.

Patented Dec. 17, 1907.

Application filed May 28, 1907. Serial No. 376,124.

To all whom it may concern:

Be it known that I, ALBERT B. DICK, a citizen of the United States, residing at Lake Forest, in the county of Lake and State of Illinois, have invented a certain new and useful Improvement in Stencil - Printing Machines, of which the following is a specification.

This invention relates particularly to that type of printing-machines wherein is employed a rotary drum upon the surface whereof is secured a waxed stencil-sheet, through the type openings in which the printing is accomplished upon a suitable impression-sheet fed between the periphery of such drum and an underlying platen, such as a pressure - roller. The ink is supplied by means of a pad arranged upon the drum beneath the stencil-sheet. The tendency of such ink when deposited upon the impression-sheet is to cause such sheet to adhere to the drum, which is one of the difficulties avoided in the apparatus of this invention. This is particularly true where the printing on the impression-sheet commences close to the advancing edge of such sheet. Where the printing upon such sheet commences at a suitable distance from the top of the sheet, the resiliency of the paper is usually sufficient to permit the same to coact with the sheet-stripers commonly employed and whose function it is to prevent the adherence of the sheet to the drum.

Under the present invention, I retain the sheet - strippers heretofore commonly employed and which extend close to the point of coaction between the periphery of the printing-drum and that of the underlying pressure-roller, but increase the efficiency and reliability of such strippers by providing, upon either side of the periphery of the drum, a sheet - guide operating to restrain the impression-sheet, along its side edges, from being brought into contact with the stencil-sheet, to which it otherwise might adhere. These guides do not preclude intimate coaction of the impression-sheet between its side edges and the operative surface of the stencil-sheet, but serve to direct such edges of the impression-sheet to the point of coaction of the sheet - strippers therewith. In a preferred form of the invention, these guides also serve measurably to protect the stencil-sheet at the forward portion thereof, which is commonly subjected to greatest wear.

They also serve to avoid accidental detachment of the forward portion of the stencil-sheet from the drum.

The invention is illustrated in the accompanying drawings, in which

Figure 1 is an end elevation, partly in section, of a stencil-printing machine embodying my invention; Fig. 2 is a cross-section illustrating a portion of the machine, particularly that part of the printing - drum which is equipped with the guides above referred to; and Figs. 3 and 4 are details illustrating modified forms in which the invention may be employed.

Referring to these drawings, it will be seen that the machine includes the side members A, A', of the frame, in which is journaled by means of suitable stub-shafts the drum B having a surface of foraminated material b secured to heads b', b''. The stencil-sheet C is secured upon this drum, the forward edge, in the present instance, by means of the "button-bar" b³, and the rearward edge by means of the bail b⁴. Said drum may be operated by means of the handle D and gears d. Directly underlying the printing-drum, is the pressure-roller E mounted upon hinged arms e and movable to operative or inoperative position by means of the shaft e' and cam e². Extending inwardly from each of the side members A, A', of the frame, is a projection F forming part of the tension device for the pressure-roller E and in addition carrying a sheet-stripper f, the free end whereof terminates close to the point of coaction of the stencil - carrying drum and pressure - roller. As will be understood, the strippers f, one carried by each of the projections F, lie on either side of the machine in such position that the edges of the impression-sheet f' will pass below the same and thereby be prevented from adhering to the surface of the stencil.

Turning now to the sheet-guides, these are here shown as forming adjuncts of the stencil-printing drum, being secured to and carried by said drum adjacent to the heads forming part thereof. In the preferred form, illustrated in Figs. 1 and 2, these guides are shown as pivotally mounted upon said drum. Since they are both the same in construction, but one need be described in detail. As best shown in Fig. 2, the guide G is pivoted at g to the inner surface of the head b' through an offsetting boss g' and takes the form of an

arm, the rearward portion g' whereof, when the guide is in operative position, extends over the button-bar b^3 to which the forward edge of the stencil C is secured and over the 5 forward portion of the stencil secured upon said bar but only adjacent to the side margins of said stencil. The outer edge g^2 of said guide G extends beyond the periphery of the head b' and beyond the periphery of the 10 drum of which said head forms part. Said guide G is also provided with means for locking the same in either its operative or inoperative position, said means comprising a pin g^3 extending through said guide G and adapted 15 to coact with either of two springs g^4 , g^5 secured to the head b' at g^6 and lying between said guide and the inner surface of said head. That portion of said pin projecting inwardly 20 from the inner surface of said guide may be used as a handle with which said guide may be thrown to one or the other of its two positions. In either of said positions, it is held against accidental displacement by means of said springs g^4 or g^5 . In its inoperative position, 25 said guide is held within the drum and therefore out of the way. This is the position to which both the guides are thrown when it is desired to remove a stencil-sheet or to place a new stencil-sheet in position. After 30 the old stencil has been removed and a new one substituted, the guides may readily be moved by means of the inwardly projecting ends of the pins g^3 to their operative position, in which they are illustrated in the 35 drawing, in which position they will be held by the springs g^5 above described. In this position, in addition to affording protection to the stencil-sheet over a substantial part of its forward end, said guides have the effect 40 of increasing the diameter of the printing-drum at the points of their location, as a consequence whereof the side margins of the impression-sheet, at the forward edge of such sheet, are turned somewhat away from the 45 periphery of the drum, leaving a space of sufficient size for the introduction of the free ends of the sheet-stripers f as the movement of the drum, and therefore that of the impression-sheet, is continued. As a result, 50 no matter how close to the advancing edge of the impression-sheet the characters of the stencil-sheet are imprinted, the tendency of the impression-sheet to adhere to the stencil, under the influence of the ink, is overcome 55 and the strippers are enabled to separate said sheet from said drum and permit the same to fall upon the support of the machine or into a suitable tray placed rearward of the machine for that purpose.

60 In Figs. 3 and 4, I have illustrated two modifications of the construction herein described, the former of these comprising a sleeve H adjustably mounted upon the stub-shaft h of the stencil-carrying drum, so that 65 in order to renew the stencil-sheet upon said

drum said sleeve may be slid upon said stub-shaft toward the left, thereby exposing the foraminated surface of said drum. After the stencil has been placed in position, the sleeve may be moved to the position illustrated in Fig. 3 and there secured by any suitable means, as, for instance, the set-screw h' . In Fig. 4, the head is shown as recessed for the reception of the foraminated stencil-carrier, leaving an annular projection h^2 having the effect to increase the diameter of the drum as a whole, adjacent to the edges of such drum, the portions h^2 therefore serving, like the sleeve H, to slightly depress the lateral edges of the impression-sheet h^3 so as to guide the same beneath the free ends of the sheet-stripers f.

Having now described my invention, what I claim as new therein and desire to secure by Letters Patent is as follows:

1. The combination with a printing-drum and an underlying platen, of sheet-stripers adapted to coact with an impression-sheet fed to said drum, and means carried by said drum and operating, when in normal, fixed position, to increase the diameter thereof at points corresponding to the lateral edges of said sheet, substantially as described.

2. The combination with a printing-drum and an underlying platen, of guides mounted in position to coact with the lateral edges only of a sheet on said drum, said guides being secured to and normally extending in fixed position beyond the periphery of said drum, substantially as described.

3. The combination with a rotatable printing-drum and an underlying platen, of guides secured to the drum and movable relatively thereto, independently of the rotation of the drum, to operative and inoperative positions, said guides normally and when in operative position extending fixedly beyond the periphery of the drum, substantially as described.

4. The combination with a movable printing-drum and an underlying platen, of guides secured to and extending beyond the periphery of said drum, and means independent of the movement of said drum for throwing said guides to operative and inoperative positions, in the former of which such guides extend fixedly beyond the periphery of said drum, substantially as described.

5. The combination with a printing-drum and an underlying platen, of guides secured to and extending beyond the periphery of said drum, means for throwing said guides to operative and inoperative positions, and mechanism for retaining said guides in either of said positions, substantially as described.

6. The combination with a printing-drum and an underlying platen, of means carried by said drum and coacting with an impression-sheet fed thereto to bend the lateral edges of such sheet out of a plane, said means

extending over the forward edge of the stencil-sheet upon said drum adjacent to its side margins, substantially as described.

7. The combination with a printing-drum and an underlying platen, of a guide pivotally mounted upon said drum and extending beyond the periphery thereof, said guide being movable to operative and inoperative positions, in the latter of which it overlies and protects the forward edge of the stencil upon said drum adjacent to its lateral edges, substantially as described.

8. The combination with a printing-drum and an underlying platen, of a guide carried by said drum and normally extending fixedly beyond the periphery thereof said guide being movable to operative and inoperative positions, a pin carried by said guide, and a spring coacting with said guide to retain the same in either of said positions, substantially as set forth.

9. The combination of a printing-drum, means for rotating the same, an underlying platen, and guides secured to said drum and

movable relatively thereto to operative and inoperative positions, said guides when in operative position extending beyond the periphery of the drum and being held stationary relatively to the drum throughout the rotation thereof, substantially as described. 30

10. The combination of a printing-drum, means for rotating the same, an underlying platen, and guides secured to said drum in position to coact with the lateral edges only of a sheet on the drum, said guides being movable relatively to the drum to operative and inoperative positions and when in operative position extending beyond the periphery of the drum, in which position they are held stationary relatively to the drum throughout 40 the rotation thereof, substantially as described.

This specification signed and witnessed this 25th day of May, 1907.
